US0D1057774S

(12) **United States Design Patent** (10) Patent No.: **US D1,057,774 S**
(45) Date of Patent: ** Jan. 14, 2025

(54) **HANDLING APPARATUS**

- (71) Applicant: **MANITOU BF**, Ancenis (FR)
- (72) Inventors: **Alexander Prokopowicz**, West Bend, WI (US); **Cade Allecox**, West Bend, WI (US); **Thierry Lehmann**, Ancenis (FR); **Arthur Beaulieu**, Ancenis (FR); **Gale Vogt**, Yankton, SD (US); **Seth Koertner**, Yankton, SD (US); **David Christensen**, Yankton, SD (US)
- (73) Assignee: **MANITOU BF**, Ancenis (FR)
- (**) Term: **15 Years**
- (21) Appl. No.: **29/938,589**
- (22) Filed: **Apr. 22, 2024**

Related U.S. Application Data

- (62) Division of application No. 35/516,801, filed on Feb. 10, 2023 (U.S. filing date under 35 U.S.C. 384), and having an international filing date of Feb. 10, 2023.

(57) **CLAIM**

The ornamental design for a handling apparatus as shown and described.

DESCRIPTION

FIG. 1 is a front right perspective view of an ornamental design for a handling apparatus;
FIG. 2 is a right side view of the handling apparatus of FIG. 1;
FIG. 3 is a rear right perspective view of the handling apparatus of FIG. 1;
FIG. 4 is a rear view of the handling apparatus of FIG. 1;
FIG. 5 is a rear left perspective view of the handling apparatus of FIG. 1;
FIG. 6 is a left side view of the handling apparatus of FIG. 1;
FIG. 7 is a front left perspective view of the handling apparatus of FIG. 1;
FIG. 8 is a front view of the handling apparatus of FIG. 1; and,
FIG. 9 is a top plan view of the handling apparatus of FIG. 1.
